Des. 238,785
Patented Feb. 10, 1976

238,785

COOL VAPOR HUMIDIFIER

Andrew J. Alger, Chicago, Ill., and Eugene R. Luedtke, Reedsburg, Wis., assignors to Gerber Products Company, Fremont, Mich.

Filed Jan. 29, 1975, Ser. No. 545,247

Term of patent 14 years

Int. Cl. D23—04

U.S. Cl. D23—146

FIG. 1

FIG. 2

FIG. 5

FIG. 3

FIG. 4

FIG. 1 is a front perspective view of a cool vapor humidifier showing our new design;

FIG. 2 is a top plan view;

FIG. 3 is a front elevational view;

FIG. 4 is a left side elevational view, the right side being a mirror image thereof;

FIG. 5 is a bottom plan view.

FIGS. 2 through 5 are shown on a reduced scale for ease of illustration.

We claim:

The ornamental design for a cool vapor humidifier, as shown and described.
